UNITED STATES PATENT OFFICE.

GUSTAV B. PETSCHÉ, OF YONKERS, NEW YORK.

ROTARY PUMP.

1,380,014.

Specification of Letters Patent. Patented May 31, 1921.

Application filed September 25, 1920. Serial No. 412,822.

To all whom it may concern:

Be it known that I, GUSTAV B. PETSCHÉ, a citizen of the United States of America, and resident of Yonkers, county of West Chester, State of New York, have invented a certain new and useful Improvement in Rotary Pumps, of which the following is a true and exact description, reference being had to the accompanying drawings, which 10 form a part thereof.

My invention relates to rotary pumps having rotary eccentric ring pistons provided with an extension forming a partition between the admission and discharge sides 15 of the pump in connection with an oscillating shoe articulated to the piston extension and moving in a bearing having the form of a segment of a cylinder. The chief object of my invention is to provide a pump of this 20 kind with a valve which will close the admission port during the period when the eccentric ring piston is passing from the close of its propelling cycle to the beginning of its intake cycle to prevent a free 25 passage between the discharge and suction pipe. A further object of my invention is to cheapen the cost of such pumps by so locating the cylindrical bearing of the shoe 30 that it can be bored out in a boring mill.

The nature of my improvements will be best understood as described in connection with the drawings in which they are illustrated and in which—

Figure 1 is a side elevation of my improved pump taken on the section line 1—1 of Fig. 2.

Fig. 2 is a front elevation of the pump partly in section on the line 2—2 of Fig. 1.

Fig. 3 is a view similar to Fig. 2 showing the parts in the position they occupy when the admission valve is closed.

Fig. 4 is a face view of the pivoted lever on which are formed the shoe and the admission valve.

Figs. 5 and 6 are diagrammatic views illustrating modifications of my invention.

A and A' indicate air pump cylinders formed in the same casting and provided with face plates, A² and A³. B indicates 50 the cylindrical face of the pump cylinder interrupted at B' where the delivery port is located and at B² where it is intersected by the bearing C. C is a cylindrical bearing for the shoe and valve to be described.

D is the delivery port of the cylinder and E the admission port, the admission port

being formed, as shown, in the bearing C. F is the driving shaft of the pump to which is secured the eccentric F' on which work the eccentric ring pistons G having arms G' 60 extending between the delivery and admission ports of the pump and articulated at K to a sliding shoe J which moves on the cylindrical bearing C being carried by an arm I pivoted at H. L is a similar arm supporting the admission valve M.

Referring to Fig. 5, C' indicates a cylindrical bearing. M' a slide which serves both as a shoe and as an admission valve; this slide being supported on the lever I' L' pivoted at H and necessarily extending in this case without perforations between the side walls of the bearing. The extension G' of the piston being pivoted to the arm I' and K'. 75

In the modification shown in Fig. 6 the cylindrical bearing is indicated at C². D² indicates the admission port and M² a slide which serves both as a shoe and admission valve being pivoted on the center H by 80 means of a lever L². The piston extension G' is articulated to the valve at K².

In operation the piston rotates in a clockwise direction and it will be observed that in passing through the part of this path indicated in Fig. 3 that is after the completion of the propelling cycle and immediately before the beginning of the second propelling cycle, the piston leaves contact with the face of the cylinder on both sides but 90 immediately before leaving contact with the cylinder at the point B' the valve H closes the admission port E and keeps it closed until the piston has contacted with the cylinder on the opposite side at or about the point B². In this way any backward flow of fluid is prevented. It will be obvious that what I have said as to the construction of Fig. 1 is equally true of the constructions shown in Figs. 5 and 6, though I might 100 point out the construction of Fig. 5 is not considered desirable by me for the reason that it involves subjecting the pivot H to the full pressure of the delivery side of the pump.

I locate the bearing C which is in the form of a segment of a cylinder in such relation to the cylinder chamber B that both the cylinder and the bearing C can be readily machined in a boring mill, thus materially 105 cheapening the cost of production.

Having now described my invention, what

I claim as new and desire to secure by Letters Patent, is:

1. In a rotary pump having a cylinder with admission and exhaust ports and a bearing surface in the form of a section of a cylinder formed in a chamber connecting said ports, a rotary eccentric ring piston having a partition blade extending from it, a rock lever pivoted in the center of the cylindrical bearing, a shoe movable in the cylindrical bearing and attached to the rock lever and an articulated connection between the shoe and the blade extending from the piston and serving as a partition between the ports of the pump, the novel feature which consists in forming the inlet port in the cylindrical bearing surface and combining therewith an inlet valve actuated by the rock lever and having its movements timed as described so as to close the port through that portion of the cycle when the piston is not in contact with the bore of the cylinder.

2. In a rotary pump having a cylinder with admission and exhaust ports and a bearing surface in the form of a section of a cylinder formed in a chamber connecting said ports, a rotary eccentric ring piston having a partition blade extending from it, a rock lever pivoted in the center of the cylindrical bearing, a shoe movable in the cylindrical bearing and attached to the rock lever and an articulated connection between the shoe and the blade extending from the piston serving as a partition between the ports of the pump, the novel feature which consists in proportioning and locating the segmental cylindrical bearing as described and so that the cylinder of which it forms a segment will intersect the pump cylinder only at a segment which is cut away to leave clearance for the movements of the blade extending from the piston and so that the bearing can be faced in a boring mill.

GUSTAV B. PETSCHE.
